UNITED STATES PATENT OFFICE.

HENRY BLACKMAN, OF NEW YORK, N. Y.

PROCESS OF AND APPARATUS FOR MAKING PAPER-PULP.

SPECIFICATION forming part of Letters Patent No. 530,635, dated December 11, 1894.

Application filed October 21, 1889. Renewed October 13, 1894. Serial No. 525,843. (No model.)

To all whom it may concern:

Be it known that I, HENRY BLACKMAN, a citizen of the United States, residing in New York city, in the county and State of New York, have invented certain new and useful Improvements in Processes of and Apparatus for Making Paper-Pulp, of which the following is a specification.

This invention relates chiefly to what is known as the "vacuum process" of disintegrating fibers for the manufacture of paper pulp, whether the fibers be prepared by digestion according to the alkali process or the sulphite process. This vacuum process of disintegration is the one described and claimed in my Patent No. 369,836, dated September 13, 1887.

The invention also relates in part to what is known as the "sulphurous" or "sulphite" process of disintegrating fibers.

My invention also provides the necessary apparatus for practicing the improvements in the process.

According to what is known as the "sulphurous" or "sulphite process" of making paper pulp, the wood, straw, or other fibrous matter is exposed in a digester under considerable pressure and at a high temperature, to the action of a solution of sulphurous acid, or preferably of sulphite of soda, potash, lime, or other alkali or base. The boiling is continued for several hours, during which time by the action of the sulphurous or sulphite solution, the gummy or resinous matters or other cementing substances that bind the fibers together are decomposed or dissolved, thereby freeing the pure cellulose which constitutes the essential portion of the fibers, so that at the conclusion of the digesting operation the fibrous matter is discharged as an impure pulp requiring only washing and beating to fit it for use. The digester employed consists usually of a steel shell of great strength to withstand the heavy pressure, and lined with lead to resist the corrosive action of the acid solution.

My present invention, which in its main features is not limited to the sulphurous or sulphite processes, provides an improved means for disintegrating the fibrous matter.

According to my said Patent No. 369,836, the fibrous matter was first digested under

heat and pressure in a suitable solvent, as an acid or sulphite solution, or an alkaline solution. At the end of the digesting process the 55 softened matter was disrupted by blowing it out under considerable pressure through an orifice or nozzle into a vacuum chamber. As the material passed into the vacuum chamber it was washed down and pumped out 60 therefrom and subsequently submitted to washing and scrubbing or beating operations to reduce it to the desired grade of pulpiness.

According to my present invention I perform the blowing off or disrupting operation 65 at intervals during the digesting process so that after disruption the fibrous matter is further digested. At each such disrupting operation the gaseous matter drawn off from the vacuum chamber is immediately or eventually 70 returned to the fibrous matter or solution in the digester. At one or more such disruptions the solution is drained off from the fibrous matter and fresh solution supplied to take its place, after which the fibrous matter is pumped back into the digester. From 75 time to time during the digesting process the gaseous matter is drawn off from one part of the digester and returned to another part thereof to cause it to circulate through the 80 fibers. At the end of the digesting operation the fibrous matter is blown out into the vacuum chamber and continuously pumped back therefrom into the digester, and again blown out, being thus circulated repeatedly as many 85 times as is desirable to produce the requisite degree of fineness of the pulp. Finally the charge is all accumulated in the vacuum chamber, freed from the gas and spent solution, and pumped out therefrom. 90

In order to practice my present invention, I provide one or more digesters such as are used in the well known sulphite process, and a vacuum chamber or tank to which the digester is connected so that its contents may be blown off into the vacuum chamber, which has a capacity sufficient to receive the entire charge from one digester. I also provide a pump for maintaining a vacuum in this chamber, and between the pump and vacuum chamber I provide a vapor separator and condenser. These several vessels are connected together through suitable pipes suitably provided with valves for regulating the flow of gases or 100

liquids therethrough and connected with pumps for circulating the gases or liquids.

In carrying out my invention I proceed preferably as follows:—I first boil the wood 5 chips or other fibrous matter for several hours in an open tank, using simply water, or water in which a considerable portion of soda or other alkali is dissolved. Then when the digester is ready to be charged I transfer the 10 fibrous matter and liquor to the digester; or the fibrous matter may be placed in the digester at first without being previously boiled. The digester being closed, I introduce a suitable proportion of the sulphite solution, 15 which may be a monosulphite or bisulphite either of lime, soda, or other alkaline or basic material. If the wood has first been boiled in an alkaline liquor, it may be unnecessary to add any further alkali or base, in which 20 case the sulphite liquor will be prepared in the digester by pumping in sulphurous acid gas. In any case, if the liquor does not already afford an acid reaction a suitable proportion of sulphurous acid should be forced in to 25 render it acid. The liquor or solution should cover the fibrous matter. The mass is then boiled in the digester for from twelve to sixteen hours, the necessary heat being applied by injecting steam directly into the solution, 30 or by means of a steam coil or jacket in the bottom of the digester. During the boiling the liquor is circulated through the fibrous matter in any usual way. In the case of a revolving digester this circulation will be effected by turning the digester on its trunnions. In the case of a stationary digester it 35 is effected by pumping the liquor out from the bottom and returning it to the top. From time to time the sulphurous gas is drawn off 40 from the top of the digester and being passed through the condenser is pumped back into the digester at the bottom, thereby effecting a circulation of the free gas independent of the circulation of liquid. At such times the 45 pressure may be reduced and the gas pumped out under a vacuum while the boiling is continued.

During the period of digestion the fibrous matter is "disrupted" one or more times in 50 accordance with my vacuum process of disintegration described in my aforesaid patent. This disruption is accomplished by blowing off the fibrous matter and liquor from the digester into the vacuum chamber under a considerable pressure in the digester and at a high temperature, while in the vacuum chamber a vacuum or rarefaction is maintained by the operation of the vacuum pump. The fibrous matter enters the vacuum chamber 55 through a contracted nozzle or orifice on escaping from which into the vacuum the liquid in the cells of the fibrous matter being suddenly relieved of pressure is vaporized or converted into steam which tears the fibers 60 asunder or disrupts them. The steam, vapor and gas pass out at the top of the vacuum chamber and are carried through the con-

denser in which the steam is condensed and passed thence to the pump. The fibrous matter falls to the bottom of the vacuum chamber together with the portion of the liquor which is not vaporized. During the blowing off, the disengaged gas is pumped from the vacuum pump back into the top of the digester to assist in maintaining the pressure 75 therein.

When the entire contents of the digester have been blown off into the vacuum chamber they are returned again to the digester either by pumping them back or by opening 80 valves and turning a pressure of steam into the vacuum chamber sufficient to force them to flow through the communicating pipe from the vacuum chamber into the digester. This return or transfer of the fibrous matter and 85 liquor may be assisted by forming a vacuum in the digester by connecting it with the vacuum pump. This disruption of the fibrous matter by blowing it off into the vacuum chamber and the subsequent return of the 90 fibrous matter to the digester should be practiced several times during the period of digestion. The first disruption should be effected as soon as the fibrous matter is sufficiently disintegrated by digestion to enable 95 it to be forced through the contracted nozzle into the vacuum chamber without danger of clogging, which will usually be after the digestion has continued for about four to six hours. The disruptive operation should be 100 repeated at intervals of three to four hours during the remainder of the digesting operation. At one of the disruptive operations, and preferably after the digestion has been continued about eight or ten hours the liquor 105 or sulphite solution should be changed. The fibrous matter having all been discharged into the vacuum chamber, the pressure in the latter is restored to that of the atmosphere, or to above atmospheric pressure, and 110 the old liquor is drained off from the fibrous matter. Fresh liquor or sulphite solution is then introduced into the vacuum chamber, and the fibrous matter and fresh liquor are pumped or blown back from the vacuum 115 chamber into the digester, whereupon the digesting process is resumed.

When the digestion is completed the pulp is subjected to a final disruptive blowing off into the vacuum chamber. During this blowing off it is preferable to pump the pulp and liquor back from the vacuum chamber into the digester as fast as it enters, so that it may be again blown out and kept in circulation until it has been blown through the contracted 120 nozzle into the vacuum chamber as many times as may be desired to complete the separation of the fibers. When the entire mass has thus been circulated two or more times, the pulp outlet from the vacuum chamber is closed and all the pulp from the digester is blown into the vacuum chamber. When the entire charge of pulp has been deposited in the vacuum chamber the vacuum 125

is discontinued and the spent liquor is drained off from the pulp. The pulp is then still impregnated to a considerable extent with sulphurous acid gas, for the removal of which

5 the pulp is heated while under vacuum. This is preferably accomplished by injecting steam into the bottom of the vacuum chamber so that it passes upward through the mass of pulp, the gas thus liberated and the 10 steam being drawn off by the vacuum. Thus nearly every trace of sulphurous gas is eliminated from the pulp. Hot water is then introduced into the top of the vacuum chamber and the pulp is washed out to the pump 15 which pumps it to the usual "wash tanks" where it is washed in the usual manner and is run into the usual "clean pulp chest." It may then be used in any known way for paper manufacture.

20 My present invention comprising those parts of my improved process herein described which pertain to the disruption of the fibrous matter by blowing it into the vacuum chamber, and to the return of the pulp to the digester to be again disrupted, may be practiced independently of the use of the sulphite process of disintegration, as for example in connection with the ordinary soda process.

I will now proceed to describe the new apparatus for pulp making invented by me for use in practicing the process hereinabove specified, referring for that purpose to the accompanying drawings, wherein—

Figure 1 is a general view of the apparatus 35 on a small scale chiefly in elevation but partly in vertical section. Fig. 2 is a vertical section on a larger scale of the digester, vacuum chamber, condenser, and their communicating pipes. Fig. 3 is a horizontal section of 40 part of Fig. 1, cut on the plane of the line 3—3 therein.

Referring to the drawings, A designates the digester; B, the vacuum chamber; C, the condenser; D, the vacuum pump; E, the sulphite 45 mixer; F, the recovery tank; G, one of the wash tanks, and H the boiling tank.

I, J, K and L, are pumps which may be centrifugal pumps.

The digester A may be of any known construction, such for example as either of those shown in my Patents Nos. 369,836 and 369,834 of September 13, 1887. In the construction shown it consists of a steel outer shell with an inner lining of lead as is common in working under the acid or sulphite processes, with a large opening a at its top through which to introduce the fibrous matter and an outlet a' at its bottom from which leads a pipe b connecting with a pipe b', extending to the 55 vacuum chamber B, and there terminating in a contracted nozzle or discharge orifice c.

In the bottom of the digester is fitted a conical screen or false bottom a² in the space beneath which is preferably a steam coil or jacket d, the admission of steam to which from the steam pipe S is controlled by a valve 65 5. From the space beneath the screen a², a

pipe e leads to the pump I, and a pipe e', leads from this pump to the upper part of the digester which it enters. Thus by operating 70 this pump, the liquor may be drawn down through the mass of fiber which rests on the screen a², and returned into the top of the digester, thus instituting a circulation of the liquor through the fibrous matter. The outlet a' is closed by a valve 6 in the discharge pipe b. Steam from the pipe S is admitted into the top of the digester through a valve 7.

If the tank H is not used, the inlet opening a at the top of the digester is closed by a man-hole plate as shown in Fig. 2. When the tank H is employed however, it is arranged preferably directly over the digester and communicates therewith through an outlet pipe f entering the opening a and closed by a valve 8. 85 The tank H has a perforated screen or false bottom f', in the space beneath which is a steam coil f² into which steam is admitted through the valve 9, in order to supply heat for boiling the fibrous matter in the tank. 90

The vacuum chamber B is the same in its general principle of operation as the vacuum chambers shown in my said Patents Nos. 369,836 and 369,834. Instead however of being a comparatively shallow box or chamber 95 partially divided by a pendent partition or target, it is constructed as a large upright vessel preferably cylindrical and having a capacity sufficient to receive in its lower portion the entire contents of the digester A. 100 The nozzle c enters it at one side near its top and directs the stream of fibrous matter against the target g which is arranged to project down from the top of the chamber. This target has the same function as the target 105 in my Patent No. 369,836. In the bottom of the chamber is a conical screen or false bottom g' opening downward to the outlet opening g² from which a pipe h governed by a valve 10 leads to the pump L. This pump discharges into a pipe h' from which there are two branches, one of which h², extends upward and enters the top of the digester A, being governed by a valve 11. The other branch h³, leads to the wash tank G, into which it discharges, being governed by a valve 12. 115

From the top of the vacuum chamber B a vapor pipe i extends upwardly, being provided with a valve 13, and enters a vapor separator C' which consists of a box or chamber 120 having a pendent target or partition i' in its upper part to deflect downwardly the stream of vapors flowing through the chamber on their way to the outlet pipe i². This outlet pipe leads into the top of the condenser C, 125 which may be of any construction common for condensers, and either a surface or jet condenser. The condenser shown is a jet condenser receiving cold water, preferably lime water, from the pipe W which enters the upper part of the condenser and is perforated to throw jets of water thereinto in contact with the steam and vapors, the water thus introduced being controlled by a valve 15. The 130

4
5 injected water and the water of condensation fall to the bottom of the condenser and flow off by a pipe *j* leading to the pump *J*, while the uncondensed gas and vapors, consisting chiefly of sulphurous gas and steam, flow out of the side by a pipe *k* which leads down and communicates through the two-way valve 14 with the suction pipe *k'* of the vacuum pump *D*. The uncondensed steam or vapor is condensed in this pipe *k* by cold water showered thereinto from a perforated pipe *k'*, fed by a branch from the pipe *W* and controlled by a valve 16. The vapor which is separated in the chamber *C'* flows down a pipe *v*, and is 15 discharged either through a pipe *v'* into the condenser *C* or through a pipe *v'*, back into the vacuum chamber *B*, its flow being determined by a two-way cock 17.

The vacuum in the chamber *B* is maintained by the operation of the pump *D* which 20 draws the gases or vapors out through the pipe *i*, separator *C'*, condenser *C*, and pipe *k*, the valve 14 being in the position shown in Fig. 2. In order that the same pump may 25 also serve for drawing the sulphur gas from the top of the digester *A*, a pipe *l* is provided leading from the top of the digester and communicating with the pump preferably by joining the pipe *i* above its valve 13, so that 30 by closing this valve and opening a valve 18 in the pipe *l* the gases or vapors may be drawn through this pipe and through the separator *C'*, condenser *C*, and pipe *k* to the pump.

The gases drawn off by the pump are 35 discharged through a pipe *m* in either of three different directions, namely: first, through a branch pipe *m'* governed by a valve 19 into the sulphite mixer *E*; second, through a branch pipe *n* into a long main pipe *p* which 40 extends from the pump *K* to a pipe *p'* communicating with the digester or digesters as will be presently described, the flow through the pipe *n* being governed by a valve 20; third, in case a lime tower is used the gas may 45 be discharged through a branch pipe *m'*, governed by a valve 21 and leading to the tower.

The liquid which descends from the condenser *C* and which will usually be rich in sulphurous gas, is forced by the pump *J* 50 through the pipe *j'* into the sulphite mixer *E*, this pipe being provided with a valve 22.

The sulphite mixer in addition to the inlet pipes *m'* and *j'* for gas and liquid is provided as shown in Fig. 1 with an inlet pipe *W'* for 55 admitting lime water, being governed by a valve 23; and with a pipe *M'* for admitting sulphurous gas from the retort or furnace in which this gas is produced, its admission being governed by a valve 24. In addition the 60 sulphite mixer is provided with an outlet pipe *o* governed by a valve 25, and leading to the pump *K*, by which the sulphite liquor or solution prepared in the mixer *E* is discharged into the digester or wherever else it is required.

The liquor from the sulphite mixer is pumped by the pump *K* through the pipe *p* and

thence either through the pipe *q* which enters the upper part of the vacuum chamber *B*, the flow into this pipe being governed by a two-way valve 26, or it is pumped through the entire length of the pipe *p* into the pipe *p'* and thence into the digester either through a pipe *r* or a pipe *s*. The pipe *r* enters the bottom of the digester beneath the screen *a'*, and is 75 controlled by a valve 27. The pipe *s* extends to the top of the digester, the flow through it being controlled by a valve 28. The pipe *p* is furnished with a valve 29 between the pump *K* and branch pipe *n* in order to prevent any back flow from the pump *D* through pipes *n* and *p* toward the pump *K*.

Warm or hot water is supplied by a pipe *W'*, which has two branches, one leading to the boiling tank *H* and controlled by a valve 30, 85 and the other leading to the top of the vacuum chamber *B*, and controlled by a valve 31.

The steam pipe *S* in addition to branches communicating through the valves 9 and 5 with the tank *H* and digester *A* respectively, 90 has also a branch pipe *s'* leading to the top of the vacuum chamber *B* and controlled by a valve 32, a branch *s''* leading to the bottom of the vacuum chamber beneath the screen *g'* therein and controlled by a valve 33 and a 95 branch *s'''* leading to the outlet *a'* from the digester and controlled by a valve 34. Finally the spent liquor is discharged through the pipe *w* leading to the sewer or elsewhere and governed by valve 37.

The pump *D* may draw the sulphurous gas either through the pipe *k* or from the tank *F* through the pipe *v* or from the retort in which this gas is generated through a pipe *M*, which latter pipe communicates with its suction chamber, being controlled by a valve 38.

The wash tank *G* is of any usual construction and requires no description.

Preferably two or more digesters *A* are employed, since with a single digester the 110 vacuum chamber *B*, pump *D*, recovery tank *F*, &c., would be idle the greater part of the time. In Fig. 3, I have shown in horizontal section a battery of three digesters *A A A*, all connected to the one vacuum chamber *B*. The outlet pipes *b* of the three digesters all 115 communicate with a single cross pipe *b'*, through which they are put into connection with the pipe *b''*, which extends up to the nozzle *c*. The single discharge pipe from the pump *L* enters a transverse pipe *h'* from which three vertical pipes *h''* ascend and lead to the respective digesters. The single pipe *p* communicates with a transverse pipe *p'* extending under the three digesters, and from which 125 three vertical pipes *r r* ascend and enter the bottoms of the digesters, while three pipes *s s* branch laterally from the pipe *p'* and extend to the tops of the respective digesters.

The several valves numbered from 5 to 38 130 may be of any suitable construction, some of these being gate valves, others being globe valves, and others being two-way cocks.

The general operation of the apparatus will

be well understood from the description which I have given of the process. I will however describe some of the operations of the apparatus which may not be apparent from such 5 description.

After the fibrous matter has been placed in the digester, the solution or liquor is introduced into the digester from the sulphite mixer by the pump K, flowing through the 10 pipes o, p, and either pipe r or s, according as it is desired to introduce it at the bottom or at the top of the digester. It will usually be introduced at the top, in which case the 15 valves 25, 29 and 28 will be opened.

15 In order to blow off the fibrous matter into the vacuum chamber to disrupt it, the valve 13 is opened, the two-way cock 14 is set to the position shown, and the pump D is started and operated until a sufficient vacuum is produced in the chamber B. A sufficient pressure being maintained in the digester A, the valve 6 is opened, whereupon by reason of the pressure behind it and the suction in advance the fibrous mass is forced out and flows 20 in a continuous stream through the nozzle c into the vacuum chamber. The fibrous matter falls to the bottom of the chamber and may be immediately and continuously pumped back through the pipes h, h' and h² by opening the valves 10 and 11 and operating the 25 pump L, whereby the fibrous matter will be circulated between the digester and vacuum chamber until it has passed through the nozzle as many times as may be desired, or the 30 fibrous matter may, by keeping the valve 10 closed, be permitted to accumulate in the 35 vacuum chamber.

At each intermediate blowing off or disruptive operation, the sulphurous gases in 40 the vacuum chamber are pumped back from the pump D into the digester A through the pipes m n p and s. Whenever in the course 45 of a digesting operation it is found necessary to introduce additional sulphurous gas into the digester, this is done by the pump D which draws the gas either from the pipe M, or from the recovery tank F through the pipe v, and pumps it through pipes m n p and (preferably) r into the bottom of the digester.

50 To change the liquor after any blowing off of the pulp, the valve 10 is kept closed and when all the pulp has been blown into the vacuum chamber valve 13 is closed and steam is admitted at 32 to fill the vacuum and generate a steam pressure in the chamber B, whereupon the valve 35 is opened and the liquor is forced or runs out through the pipe u into the recovery tank. Fresh liquor is then supplied from the sulphite mixer through pipe 55 o, pump K, pipe p, cock 26 and pipe q.

At the final blowing off of the pulp into the vacuum chamber the spent liquor is drawn off in the same manner, and the sulphurous gas is then driven off from the pulp by admitting steam through valve 33, so that it ascends through the mass of pulp, while at the 60 same time the valve 13 being opened, the

pump D is operated to draw off the sulphurous gas thus expelled. When the sulphurous gas has thus been sufficiently eliminated, 79 valves 13 and 33 are closed and valves 10 and 31 are opened, so that water enters the vacuum chamber and the pulp is washed down into the pump L which forces it through pipes h' and h² into one of the wash tanks G. 75

Whenever during the digestion it is desired to draw off the sulphurous gas from the digester, this is done by closing the valve 13, opening the valve 18 and operating the pump D, so that the gas is drawn off through the 80 pipe l. It may be pumped into the sulphite mixer and its place supplied by fresh gas or it may be pumped back through the pipes m, n, p and r into the digester.

If the sulphite mixer E be not used, its 85 functions may be performed in a measure by the usual lime tower, in which case instead of the liquids and gases being pumped into the tank E, the liquids will be pumped to the top of the tower and the gases be pumped into 90 its bottom, as is usual in the operation of such towers. The liquid drawn from the bottom of the tower will be conducted to the pump K which will distribute it through the pipes p, q, r and s in the manner shown. The 95 use of the sulphite mixer is preferred however on account of the greater cheapness and expedition in the recovery of the sulphurous gas and because the gas is confined so that it cannot escape to the atmosphere and give 100 rise to foul odors.

My improved process may be considerably modified in practice. The succession of operations which I have herein described is that which I consider preferable. Certain of these 105 operations however may be omitted and the several steps or operations may be performed in somewhat different successions than the precise succession described.

Although I have referred throughout the 110 specification to the use of a sulphite solution as the reducing liquor, yet it will be understood that my invention is applicable in connection with any solution into which sulphurous acid or any other equivalent gaseous solvent or reducing agent enters as a component. Thus the sulphurous acid may be used with 115 water and without any alkali or base.

It will of course be understood that equivalent devices or means may be substituted for 120 the means shown. For example, the pumps I, J, K and L, instead of being centrifugal pumps may be any other kind or construction of pump or any other apparatus known to the arts which is capable of substitution 125 for a pump to accomplish the same work. For example, a monte-jus may be substituted for the pump L; or in any case where a pump is used to transfer a liquid from one closed vessel to another, the pump may be omitted 130 entirely and the transfer be effected by establishing a difference of pressures between the two vessels, the one from which the liquid is being expelled being given an internal

pressure sufficiently greater than that in the vessel to which the liquid is being introduced to overcome the friction and other resistance opposing the flow of the liquid; or the respective vessels may be arranged at different levels so that the liquid will flow from the higher to the lower vessel upon the establishment of an equilibrium of internal pressures. The latter arrangement is shown in connection with the vessels B and F, the former being shown arranged on a higher level than the latter, so that the liquid runs off itself whenever the valve 35 is open and the pressures in the two vessels are the same or nearly so. If the tank F however were arranged on the same level as the chamber B, or at a higher level, it would be necessary to introduce a pump into the pipe u as in the case of the pumps K and L.

20 All of the modifications of apparatus and their connections together shown in my said Patents Nos. 369,834 and 369,836, in so far as the same are applicable in connection with my present invention, are to be construed as though their illustration and description were repeated in my present application. For example, the substitution for the vacuum pump D as the means for maintaining the vacuum in the vacuum chamber of an ejector as shown 25 in Fig. 5 of my Patent No. 369,836, may be made and will serve some of the purposes of my present invention.

In the foregoing specification I have referred to some processes and have described 35 and shown some apparatus which are not essential to the practice of the invention claimed herein. This has been done to disclose the entire apparatus preferably employed in the practice of my present invention, and the relation of the parts claimed to the other parts of 40 the complete apparatus preferably used in connection therewith.

The features thus shown and described which are not essential to my present invention 45 and may be omitted are the means and methods for preparing sulphite solutions and for recovering the sulphurous gases from the spent liquors and from the finished pulp, and the re-utilization of the chemical agents, the apparatus for these purposes comprising the "sulphite mixer" E and the "recovery tank" F and the several connections and appurtenances peculiar thereto, such as M, M', W', c, u, v, S', and w.

55 The features of the process and apparatus thus indicated are not claimed herein, but the essential and novel portions thereof are claimed in my application, Serial No. 354,760, filed June 9, 1890, which is a division of my 60 present application.

I claim as my invention the several improvements in the disintegration of fibrous matter for the manufacture of paper pulp and in apparatus therefor defined as follows, each substantially as hereinbefore specified, namely—

1. The improved process of preparing paper

pulp, which consists in partially digesting the fibers, then disrupting the fibers by blowing them into a vacuum, and then resuming the digestion and repeating the blowing into a 70 vacuum until the fibers are reduced to the desired fineness.

2. In an apparatus for disintegrating fiber the combination with a digester of a vacuum chamber, an outlet from the digester to the 75 vacuum chamber, a vacuum pump for maintaining a vacuum in the vacuum chamber, and an inlet pipe or passage leading from the outlet of the vacuum chamber to the digester, whereby the matter blown off from the digester into the vacuum chamber may be returned from the latter to the digester.

3. The combination with a digester having an outlet at its bottom a vacuum chamber having an inlet connected to said outlet, a 85 vacuum pump for maintaining a vacuum in said vacuum chamber, a pipe extending from the outlet in the lower part of the vacuum chamber to the upper part of the digester, and a pump for forcing fibrous matter through 90 said pipe, whereby the fibrous matter may be drawn by said pump from the vacuum chamber and forced into the digester during the blowing off of the fibrous matter from the bottom thereof into the vacuum chamber. 95

4. The combination of a digester a discharge outlet at its lower portion, a vacuum chamber having an inlet nozzle or orifice communicating with said outlet, a vacuum pump connected to the vacuum chamber to 100 draw off the gaseous or vaporous matters therefrom and a pipe connecting the discharge of said pump with the digester, whereby during the operation of blowing off the fibrous matter from the digester into the 105 vacuum chamber, the gases drawn off by the pump may be reintroduced into the digester.

5. The combination with a digester, of a vacuum chamber having an inlet nozzle or orifice at its upper part communicating with 110 the outlet from the digester, and having a screen or perforated false bottom and a pulp outlet from said screen, a pipe for draining off the liquid from the bottom of the vacuum chamber beneath said screen, and a pipe entering the upper part of the chamber whereby the fibrous matter discharged into said vacuum chamber may be drained of liquid on said screen and may be supplied with fresh liquid 115 and be discharged through the pulp outlet. 120

6. The combination with a digester of a vacuum chamber having an inlet nozzle or orifice communicating with the outlet from the digester, a vacuum pump, a pipe connecting the upper part of the vacuum chamber 125 with the suction of said pump, a steam-pipe entering the lower part of the vacuum chamber, and a pulp outlet leading from the lower part of said chamber, whereby the fibrous matter may be discharged from the digester 130 into said vacuum chamber, and while under vacuum therein steam may be forced through

the mass and the gas or vapor thereby disengaged be drawn off by the vacuum.

7. The combination with a digester and vacuum chamber of a discharge pipe from the bottom of the digester entering the vacuum chamber, a vacuum pump, a pipe connecting the upper part of the vacuum chamber with the suction of said pump, a valve in said pipe a steam pipe entering the upper part of the vacuum chamber, and a pulp outlet from the lower part thereof, whereby when a charge of fibrous matter has been introduced into the vacuum chamber the latter may be closed at the top and steam pressure introduced thereinto to blow out the charge from the bottom.

8. The combination with a vacuum chamber of a vapor pipe *i* ascending from its top, a vapor separator C' into which said pipe discharges and constructed to mechanically disengage particles of liquid from the vapor passing through it, a vacuum pump D, and

a pipe connecting the outlet of said vapor separator to the suction of said pump.

9. The combination with a vacuum chamber, of a vapor outlet pipe from the upper part thereof, a condenser into which said pipe discharges, a liquid outlet from the bottom of said condenser, a pump with its suction connected to said liquid outlet to pump away the condensed liquid, a gas or vapor outlet from said condenser, and a vacuum pump with its suction connected to said outlet for drawing off the gaseous matter from said condenser and maintaining a vacuum in the vacuum chamber.

In witness whereof I have hereunto signed my name in the presence of two subscribing witnesses

HENRY BLACKMAN.

Witnesses:

GEORGE H. FRASER,
CHARLES K. FRASER.
